Primary Examiner—Stacia Cadmus

(74) Attorney, Agent, or Firm—G. Donald Weber, Jr.

(57) **CLAIM**

The ornamental design for an automotive wheel, as shown and described.

DESCRIPTION

FIG. 1 is a perspective view of an automotive wheel showing my new design; and,
FIG. 2 is a front view thereof.

The broken line showing of environment is for illustrative purposes and forms no part of the claimed design.
